UNITED STATES PATENT OFFICE.

HERBERT E. BILLINGS, OF WOODSTOCK, ILLINOIS, ASSIGNOR TO "HEB" MANUFACTURING COMPANY, OF WOODSTOCK, ILLINOIS, A CORPORATION OF ILLINOIS.

SPARK PLUG.

Application filed July 28, 1921. Serial No. 488,109.

To all whom it may concern:

Be it known that I, HERBERT E. BILLINGS, a citizen of the United States, residing at Woodstock, in the county of McHenry and State of Illinois, have invented a certain new and useful Improvement in Spark Plugs, of which the following is a full, clear, concise, and exact description, reference being had to the accompanying drawings, forming a part of this specification.

This invention relates to spark plugs and more particularly to a self-cleaning spark plug.

It is a purpose of the invention to provide a spark plug that is self-cleaning, that is, one that keeps the porcelain thereof clean of carbon, by drawing a cleansing mixture over the same.

It is more particularly a purpose of the invention to provide a spark plug having a jacket forming a passage therearound communicating with the intake of an internal combustion engine and also communicating with the internal hollow or bore of the spark plug, so as to draw the explosive mixture, which is also a cleansing mixture, over the surface of the porcelain seated in said plug to clean the same.

It is a further purpose of the invention to provide a spark plug of the above mentioned character that is provided with such a large number of openings communicating from said passage to the interior thereof as to provide closely spaced openings separated only by small web portions, whereby the cleaning mixture is thrown against substantially the entire outer surface of said porcelain.

It is a further object of the invention to provide a detachable jacket member provided with a beveled ground shoulder engaging a corresponding beveled shoulder on the body portion of said plug to provide a tight joint between said jacket and body portion, and to provide a jacket member that is held in on the body member by a tightening nut screwthreadedly engaging said body member, thus tightening said jacket member entirely independent of the screw threaded connection between the spark plug and engine cylinder.

It is also a purpose of the invention to provide a spark plug wherein the electrodes project beyond the body portion thereof and wherein said electrodes are provided with fresh explosive mixture with each intake stroke of the engine.

It is still a further object of the invention to provide a ring-like jacket member having a suction connection that can be turned to any desired angle relative to the plug.

It is further an object of the invention to provide a check valve in said suction connection, comprising a ball mounted therein, and adapted to move between a stop on said ring and a seat in a sleeve-like member mounted in said suction connection, so as to open and close the same, said ball having a very slight movement, whereby all springs in said check valve can be eliminated.

Other objects and advantages of the invention will appear as the description of the accompanying drawing proceeds. However, I desire to have it distinctly understood that I do not intend to limit myself to the exact details shown therein and described in the specification, but that I intend to include as part of my invention all such obvious changes and modifications of parts as would occur to a person skilled in this art and as would fall within the scope of the claim.

In the drawings:

Fig. 1 is a side elevation partly in section of my self cleaning spark plug;

Fig. 2 is a section thereof taken on line 2—2 of Fig. 1; and

Fig. 3 is a view similar to Fig. 2 of a modification.

Referring in detail to the drawing, the improved spark plug comprises a body portion 5 having a threaded end portion 6 which is adapted to engage with an internally threaded opening in an engine cylinder, said body portion 5 being provided with an electrode 7. Said body portion 5 is provided with a hexagonal portion 8 which is adapted to be engaged by a wrench for screwing the plug into the engine cylinder. The body portion 5 is provided with an internal bore 9 and an internal bore 10 slightly greater in diameter than the bore 9 to provide a shoul-

der 11, said shoulder 11 being beveled and being adapted to act as a stop for the shoulder 12 on the porcelain or other insulating member 13 which extends within the bore of 5 the main body portion 5, and which is provided with a downwardly extending portion 14 in which is mounted the electrode 15 which cooperates with the electrode 7. Mounted between the porcelain 13 and the 10 shoulder 11 is a brass or other metallic washer 16. The porcelain is held in place by means of the bushing 17 having the hexagonal portion 18 which is adapted to be engaged by a wrench for turning the same, 15 said bushing 17 engaging the shoulder 19 on the porcelain 13 and having a packing 20 interposed between the same and the porcelain. The outer end portion 21 of the porcelain 13 is provided with a binding screw 22, to which a wire from the ignition system may be connected.

The main body portion 5 is provided with a beveled face 23 which is conical in form, and which is provided substantially 25 midway thereof with an annular groove 24 extending therearound. The outer face of the member 5 at 23 is ground to the proper bevel, and a ring 25 which forms a jacket is adapted to seat thereon, said ring 25 being 30 provided with a ground beveled face 26 corresponding to the face 23. The body portion 5 is also provided with a threaded portion 27 which is adapted to be engaged by the nut 28 so that when the nut 28 35 is turned down on the threads 27, the nut 28 will engage with the ring 25 and force the same downwardly on the body portion 5 so as to clamp the beveled faces 23 and 26 together to form a tight joint.

40 Extending inwardly from the groove 24 is a plurality of equi-distantly spaced passages 29 separated by web portions 30. As shown in Figs. 1 and 2, the passages 29 may be formed by cutting the same with 45 a circular cutter, so as to form a wide cut, and expose substantially the entire outer surface of the portion 14 of the porcelain 13 to the stream of gas or air passing inwardly from the same into the interior of 50 the body portion 5. This will be clear from Fig. 2. If desired, however, a large number of openings can be drilled as shown in Fig. 3, said openings being indicated by the numeral 29' separated by the webs 55 30'. It will be noted from Fig. 1 that the passages extend at an angle to a section that would be perpendicular to the axis of the plug so that the stream of gas or air passing from the same inwardly thereof 60 to the porcelain will be directed at an angle against the same. The ring 25 is provided with a hollow boss or tubular extension 31 and has a pair of openings 32 therein connecting the interior 33 of the 65 boss or tube 31 with the passage 24 formed

by placing the ring 25 over the groove. The tubular portion 31 is provided with a shoulder 34 and with a sleeve 35 mounted therein, said sleeve 35 being provided with a seat 36 at the end thereof for the ball 37. The outer end of the tube 31 is provided with a nut 38 which engages with the enlargement 39 on the pipe 40 for providing a tight connection between the suction pipe 40 and the tubular member 31. 70 The ball 37 is adapted to move between the shoulder 32 and the end of the sleeve 35. Said ball has a very small amount of play and will move from the opened position against the shoulder 34 to the closed position against the seat 36 at the end of the sleeve 35 without the necessity of providing a spring for this movement, the ball moving such a slight distance that the pressure of the gas in the cylinder will close 80 the valve. The suction pipe 40 is connected with the intake manifold of the engine so that as the suction stroke of the cylinder, to which the spark plug is connected, takes place, the explosive mixture 90 is drawn through the pipe 40 past the valve 37 through the passages 32 into the passage 24 and then through the passageway 29 or 29' as the case may be, when it strikes the porcelain 13 at the tapered portion 14 thereof that carries the electrode 15 and as this mixture strikes substantially the entire outer surface of the porcelain at this point at a considerable velocity, and as the mixture contains gasoline, which is 100 a cleaning agent, the porcelain of the plug will be effectively cleaned over the entire exposed surface thereof, and short circuiting of the plug due to carbon is thus prevented. 105

It will be noted that the electrodes 7 and 15 extend beyond the plug as is customary, and it is unnecessary that these be cleaned by the explosive mixture, as the carbon thereon does not do the damage 110 that is caused by carbon on the porcelain which will short circuit the plug.

It will also be noted that due to the fact that the explosive mixture is drawn through the plug, a rich clean mixture will be presented at the electrodes, thus avoiding any difficulty due to improper scavenging of the engine which would be liable to cause a burnt and non-explosive gas to be present 115 adjacent the electrodes.

Having thus described my invention, what I desire to claim and secure by U. S. Letters Patent is:

A spark plug of the character described, comprising a shell having a body portion provided with a longitudinal bore having an unrestricted opening in one end thereof, an electrode carried thereby, an insulating member mounted in said bore and spaced 125 on all sides from said body portion, an 130

electrode mounted therein, said electrodes extending outwardly beyond the end of said shell, whereby firing of said plug occurs outside the shell thereof, said shell having an annular passage therein and openings leading from said passage into said bore near the inner end thereof, said openings being

inclined at an oblique angle to the axis of said plug, and a suction connection leading into said annular passage.

In witness whereof, I hereunto subscribe my name this 22nd day of July, A. D. 1921.

HERBERT E. BILLINGS.
